LIQUID DISPENSING APPARATUS

Joseph C. Woodford, Wayne, and Joseph E. Fernly, Conshohocken, Pa., assignors to John Wood Manufacturing Company, Inc., Conshohocken, Pa., a corporation of Delaware

Application March 18, 1940, Serial No. 324,628

1 Claim. (Cl. 221—84)

Our invention provides a hose nozzle which may be advantageously employed in dispensing motor gasoline into automobile tanks. However, it may be employed in dispensing any liquid. It is ordinary practice to dispense such gasoline from a subjacent tank through apparatus including a pump and a flexible dispensing hose provided with a manually operative valve in a nozzle at its end, such a nozzle including a rigid tube which is bent at its end so that it may be thrust into the inlet of an automobile tank. However, in many instances when an automobile is driven up to a gasoline dispensing pump, the inlet to the automobile tank is at the far side of the automobile, with respect to the pumping unit, and frequently the standard length of hose with which such pumps are equipped is not long enough to enable the attendant at the pump to properly insert the dispensing nozzle in the automobile tank inlet. Moreover, many automobile tanks have inlet pipes so constructed that the rigid tube of an ordinary hose nozzle is not of sufficient length to enable the attendant to place the end of the nozzle in the tank in such position as would prevent the gasoline from splashing out the top of the open inlet when the nozzle valve is opened fully. Therefore, it is the object and effect of our invention to provide the rigid tube of such a hose nozzle with a sleeve which is mounted to reciprocate thereon telescopically, so that, when necessary or desirable, the effective length of the nozzle tube may be increased by thrusting the sleeve outwardly on the tube to any extent necessary to engage the nozzle in an automobile tank, or other receiver.

As hereinafter described, we find it preferable to make the rigid tube of the nozzle of circular cross section, with its axis extending arcuately, and to make the sleeve flexible by forming it of a helically wound strip having interlocking edge flanges, and to provide means for frictionally engaging the sleeve with said tube to detain the sleeve in longitudinally adjusted position.

Our invention includes the various novel features of construction and arrangement herein-after more definitely specified.

In said drawings; Fig. I is a side elevation of a hose nozzle conveniently embodying our invention.

Fig. II is a fragmentary sectional view of said nozzle, on a larger scale than Fig. I.

In said figures; the nozzle includes the casting 1 which forms a casing for the valve 2 which is normally pressed by the spring 3 to close the port 4, but may be opened by the operator press-

ing the handle lever 5 upwardly against the valve stem 2^a to lift the valve 2 from its seat 1^a. Said casting 1 is rigidly connected, by its screw thread 1^b, with the nozzle member 6 which forms a casing for the check valve 7 which is continually stressed by the spring 8 to close the port 9, until the pressure of the liquid through said casting 1 and through port 4 is sufficient to displace said valve 7 from its seat 6^a and permit the liquid to flow into the rigid nozzle tube 11 which is rigidly connected to said nozzle member 6 conveniently by solder 6^b.

Said rigid nozzle tube 11 is preferably of circular cross-section with its axis extending arcuately as shown in Fig. I, and a radially projecting annular abutment bead 11^a at its outer end and has the annular groove 11^b in spaced relation with said abutment.

The flexible sleeve 12 is mounted to be reciprocated longitudinally on said tube 11 between said abutment 11^a and groove 11^b. We find it convenient to form said sleeve 12 of a helically wound strip of metal 12^a having interlocking edge flanges 12^b and 12^c, as shown in Fig. II. However, it may be otherwise formed in any convenient manner.

In order to detain said sleeve 12 in any position on said rigid nozzle tube 11 to which it may be adjusted by the operator; we provide means for continually frictionally engaging said sleeve with said tube, conveniently the resilient ring 14 formed of a helically wound wire spring. Said ring 14 is of such size that it must be stretched over said tube 11 and will snap into said groove 11^b when in registry therewith as shown in Fig. II. Said ring 14 is carried at the inner end of said sleeve 12 in the screw cap 15 which is engaged with the screw thread 16^a on the collar 16 which is rigidly connected with the inner end 40 of said sleeve 12. Said collar 16 has the stop flange 16^c extending inwardly therefrom toward said tube 11, which encounters the bead 11^a when said sleeve 12 is thrust to the outer limit of its range of movement on said nozzle 11.

Said cap 15 also carries the flexible seal 17 which may be formed of leather or any other suitable material. The inner edge of said seal is continually pressed against the outer surface of said tube 11, by the coiled wire spring ring 18, and the outer edge of said seal is held between the washer 19 and the spacing ring 20, which latter has its outer end pressed by the washer 21 bearing against the inner face of said collar 16.

Although we prefer to include both the ring 14 and seal 17 to frictionally engage the sleeve

12 with the tube 11; said seal will suffice to detain the sleeve in adjusted position, without the assistance of the ring 14. Of course, the axis of the tube 11 may be straight instead of curved, and whether it is arcuately curved or straight, a rigid sleeve may be substituted for the flexible sleeve 12, in telescopic relation.

Therefore, we do not desire to limit ourselves to the specific construction, arrangement, or method of operation above described, as it is obvious that various modifications may be made therein without departing from the essential features of our invention as defined in the appended claim.

We claim:

In gasoline dispensing apparatus; the combination including a hose nozzle comprising a rigid

5 tube of circular cross section; a radially projecting annular abutment bead on the outer end of the tube; an annular groove in the tube in spaced relation with the abutment; a flexible sleeve, mounted to be reciprocated on the tube between the abutment and groove, formed of a helically wound strip of resilient metal having interlocking edge flanges; means for continually frictionally engaging the sleeve with the tube, including 10 a resilient ring carried at the inner end of the sleeve; resilient sealing means between the tube and sleeve; and means adapted to limit the outward movement of the sleeve on the tube, including 15 a flange on the sleeve arranged to encounter the abutment.

JOSEPH C. WOODFORD.

JOSEPH E. FERNLY.
